UNITED STATES PATENT OFFICE

FRED M. HOLLINGSWORTH, OF GREENFIELD, CALIFORNIA

WIRE STRETCHER

Application filed June 6, 1927. Serial No. 196,949.

My invention relates to improvements in wire stretchers and splicers, and one object is to produce a device of this character which is light in weight and can therefore be easily 5 carried about when constructing or repairing fences.

Another object is to provide a device in which broken wires of various lengths may be quickly and securely spliced without loss 10 of tension, as for instance, when the splice is made by hand.

A further object is to provide a device in which different leverages can be obtained through the intermediary of a sliding member 15 forming a part of the invention.

In order that the invention may be fully understood reference will now be had to the accompanying drawings, in which:

Fig. 1 is a plan view of the device.
20 Fig. 2 is a side elevation of the device.

Fig. 3 is an inverted plan view of the device.

Fig. 4 is a cross section of the device on line 4—4 of Fig. 1.

25 Fig. 5 is a broken plan view of the device showing how slack is taken up in a fence wire preparatory to securing the latter to a fence post.

Fig. 6 is a broken inverted plan view of 30 the device showing the initial operation for splicing two ends of a broken fence wire.

Fig. 7 is a similar view to Fig. 6 with the device turned a little more than a half revolution to cause the broken ends of the wire 35 to cross each other preparatory to looping them together.

Fig. 8 is a view similar to Figs. 6 and 7, excepting that the device has been turned a complete revolution to complete the looping 40 of the two broken ends of the wire together.

In carrying out the invention I employ a lever 2 which is slightly bowed upwardly at its ends as shown by Fig. 2, and provided with notches 4 along its oppositely disposed longitudinal margins in order to receive and hold 45 certain elements of a sliding member 6, which will be explained in detail hereinafter. A longitudinal reinforcing rib 8 is formed on the underside of said lever 2 in order to give 50 the necessary strength and rigidity thereto.

10 designates a plurality of teeth or fulcrum points projecting from the curved forward end of the lever 2 for successively engaging a fence post such as A, Fig. 5, when a wire B is being stretched preparatory to 55 being secured upon said post.

16 designates two balancing spurs projecting from the central portion of the forward end of the lever 2. The points 18 of said spurs 16 are spaced apart to retain the 60 lever 2 in approximately a horizontal position and prevent it from swinging up or down while in the act of stretching a wire, as will hereinafter appear. The rear end of the lever 2 has an eye 20 for the reception of 65 a rope, not shown, which may be tied at one end to said lever and tied at its opposite end to a post or other object for the purpose of leaving both hands of the operator free for stapling a wire to the fence post.

In order that the broken wires of a fence can be readily spliced, I provide a series of hook-shaped projections and other elements which will now be described, and which are formed upon the longitudinal rib 8. 22 designates a centrally disposed stud or projection for looping the ends of a broken wire D, together, said stud having sufficient thickness for preventing the wire from bending 70 too sharply and breaking. The stud 22 is 75 tapered towards its free end and rounded off at two corners 23, so that the partially looped ends of the wire D will slide from said stud 22 and become interlocked as the operator continues to rotate the lever.

24 and 26 designate two hooks projecting laterally from opposite sides of the rib 8 for use in making splices where only a small amount of slack is to be taken up in the broken wire.

28, 32, 30 and 34 designate two pairs of hooks depending from the rib 8 and spaced at opposite sides of the stud 22 for use in making splices where more slack is to be taken up in the broken wire, and 33 and 35 designate a pair of hooks depending from the rib 8 and spaced a greater distance than the hook 34 from the stud 22 for use in making splices where the maximum amount of slack is to be taken up.

Referring in detail to the slidable member 6, the same consists of a plate having a projecting intermediate portion 36 which forms a broad bearing surface and prevents said plate from tipping upon the lever 2 when a wire is being stretched preparatory to being secured to a fence post. The member 6 is slidably held upon the lever 2 by a pair of oppositely-disposed L-shaped elements 38 which engage the under side of said lever and are prevented by the enlarged ends of the latter from coming off and getting lost. The member 6 is provided at its ends with ears 40 and 42 having V-shaped notches 44 and 46 and around which a fence wire may be wrapped, as will hereinafter appear. The elements 38 are also provided with notches 48 for receiving the wire and coacting with the notches 44 and 46 in preventing said wire from slipping off the ears 40 and 42.

The upper surface of the member 6 is provided with two oppositely-disposed studs 49 and 50 which are riveted over a pair of washers 52 and 54, respectively, which cooperate with the ears 40 and 42 in holding the wire while being stretched from slipping off the device. The member 6 when extending transversely across the lever 2 may be freely slid to either of the enlarged ends of the latter, but can be locked at any point when turned at an oblique angle to carry the L-shaped elements 38 into the notches 4 along the longitudinal margins of said lever.

Due to the bowed ends and the lowered center of the lever 2, said ends are in approximately the same horizontal plane as the studs 49 and 50 while a wire is being stretched, and hence the latter will exert a balanced pull upon said lever and not tend to swing the rear end thereof up or down.

In the construction of a wire fence, one end of the wire B is secured to a fence post while its opposite end is secured to the device. If the wire is of considerable length so that a large amount of slack will have to be taken up the member 6 is slid rearwardly upon the lever 2 towards the eye 20. The wire is then drawn fairly taut by hand and passed around the stud 49 and twisted around the ear 40, while one or two of the fulcrum points 10 on one side of the lever 2 are placed against the post A as shown by Fig. 5. The lever 2 is then pulled around from the full line to the dotted line position, Fig. 5, or as far as is necessary to take up the slack in the wire. The body of the operator may then be pressed against the lever 2 to hold it in the dotted line position and thus leave both hands free to staple or otherwise secure the wire to the post A. While the lever 2 is held by the body as stated, said lever is prevented from swinging upwardly or downwardly by the balancing member 16, the points 18 of which firmly engage the post. Furthermore, there is little or no tendency of said lever to tip

upwardly or downwardly as the pull is approximately in a horizontal plane from the stud 50 to the forward end of the lever 2. While the lever 2 is being pulled around from the full line to the dotted line position the slidable member 6 is prevented from slipping by the L-shaped elements 38 engaging two of the notches 4 at opposite sides of said lever.

When the broken ends of a fence wire D are to be spliced, the lever 2 is inverted and said broken ends are connected to such of the hooks on the rib 8 as will take up the necessary slack when the lever 2 is rotated about the axis of the stud 22. In Fig. 6 I have shown one of the broken ends secured to the pair of hooks 28 and 32 and the other broken end secured to the hooks 30 and 34. The lever 2 is then rotated in the direction of the arrow a, Fig. 6, to cause the two broken ends to cross each other as shown by Fig. 7. As the operator continues to rotate the lever the crossed ends of the wire slip off the stud 22 due to the taper thereof and its two rounded corners 23. Further rotation of the lever 2 causes the crossed ends of the wire to become interlooped as indicated at E, Fig. 8. After the lever 2 has been rotated a little more than a complete revolution the broken ends are removed from the studs 28, 32, 30 and 34 and wrapped by hand around the main portions of the two sections of the wire to complete the splice.

From the foregoing description it is apparent that I have provided a device whereby wires may be stretched in the construction of fences, or broken wires may be readily spliced, and while I have shown the preferred embodiment of my invention I reserve all rights to such changes and modifications as properly fall within the spirit and scope of the invention as claimed.

Having thus described my invention, what I claim and desire to secure by Letters Patent is:

1. In a device of the character described, a lever having notches in two of its oppositely disposed longitudinal margins, a member slidably mounted upon said lever and provided at its ends with ears, and L-shaped elements extending from said member to the underside of the lever and adapted to enter any of said notches when said slidable member is turned obliquely to the longitudinal axis of said lever.

2. In a device of the character described, a lever having notches in two of its oppositely disposed longitudinal margins, a member slidably mounted upon said lever and having means for entering any of said notches when said member is turned obliquely to said lever, wire-engageable studs projecting upwardly from said slidable member, and washers secured to said studs.

In testimony whereof I affix my signature.

FRED M. HOLLINGSWORTH.
